PULLEY BLOCK

Application filed May 9, 1925. Serial No. 29,058.

My invention relates to the art of pulley blocks. More particularly, my invention relates to such a pulley block as may be readily disassembled and reassembled without special tools or equipment.

My invention will be described with particular reference to the conditions obtaining in the logging industry. However, my invention is not to be considered as limited to any such specific application, but is to be considered as extending to all fields where like conditions and problems obtain.

In logging, it is necessary to carry the tackle up steep slopes into locations very difficult of access. Thus, it is customary for the tackle to be carried manually up steep slopes, over fallen timber and through under-brush, so that it is positively essential for efficient operation to have the pulley blocks constructed in a manner which will permit of their being assembled and disassembled readily and without the carrying of special tools. The extensive scale, upon which logging is now conducted, requires blocks of large size, often weighing several hundred pounds. In logging, the block, which is thus most frequently transported and is of a size that it must be disassembled, is known as a "corner" block. Therefore, a primary object of my invention is to provide a block which may be readily disassembled, the parts carried by separate individuals, and then capable of being readily reassembled at the point where it is desired to mount the block.

In thus providing such a block, it is desirable to have the side members in separate parts. As these side members are the mounting means for the pin, upon which the sheave is mounted, it will be manifest that these side members must be maintained in parallel position. The method of construction heretofore obtaining was such that when the block was disassembled once or twice, the fitting of the parts was lost, because the construction involved in the first instance a driving fit. That is, the pin, in particular, which constitutes the mounting shaft for the sheave, is ordinarily of straight walled or cylindrical form, and the hole in the side members in which the ends of this mounting pin are

located is of such size that it is necessary to drive the pin through the same, and then a nut is tightly secured to the threaded end of the pin. Thus, the driving in and use of this pin very quickly reduces the nicety of fitting, the loss of which immediately results in a play which very quickly develops a decided misalignment of the sheave, and since these pulley blocks are often called upon to stand stresses of from forty to fifty tons, such misalignment readily results in breaking the block or rendering it unfit for further use. A primary object of my invention is to provide a block of such construction that it may be disassembled and at the same time the proper degree of nicety of fitting of the parts shall not be lost by such disassembling and reassembling. A further primary object of my invention is to provide a block of the character described, which will also be characterized by a great reduction in its weight, owing to the disposition and form of the parts constituting my invention.

The above mentioned general objects of my invention, together with others inherent in the same, are attained by the device illustrated in the following drawings, the same being merely a preferred exemplary form of embodiment of my invention, throughout which drawings like reference numerals indicate like parts:

Figure 1 is a view in side elevation of a pulley block embodying my invention;

Fig. 2 is a view in end elevation and partly in section of the same;

Fig. 3 is an enlarged view of one end portion of the mounting pin and associated side member;

Fig. 4 is an enlarged view in section on dotted line 4, 4 of Fig. 3; and

Fig. 5 is a view in cross section on line 5, 5 of Fig. 3.

The shell of the block is made in two pieces or side mounting members 6 which, when assembled, are held together at the top by the shackle 7 and pins 8. The pins 8 have a slot-like opening 24 adapted to operate as a wrench for a set screw 23. Also, said pins are preferably provided with a square-cornered head 25, so that pins 8 may be used as

a drift in removing keys 11. These pins 8 are secured in place by the cotter pins 9. The two parts of the shell are further held together by the pin 10, having tapered end portions 26 and the tapered keys 11. I prefer to make the pin 10 with tapered ends and ream the holes in the shell or side members with taper to correspond, so that when the keys 11 are driven through the slotted holes 12 in the pin, the keys bearing on the tapered seat 13 at the bottom of the key way 14 in the shell or side member 6 secure a rigid connection of the shell to the pin 10. The shell is also provided with recesses 22 above the keyways 14 into which the pins 8 are inserted for drifting out keys 11.

The keys 11 are secured against accidental backing or dropping out by the set screws 23, which are secured down firmly after the keys 11 are driven home. The keys 11 are provided with a longitudinal groove 15, shown in section in Fig. 5. The points of the set screws 23 enter this groove. The groove 15 terminates near the smaller end of the key, so that when the set screws are loosened sufficient to allow the keys 11 to drop clear of the pin 10, they are still prevented from falling completely out and are retained in position to be quickly driven home when the block is reassembled.

The pin 10 has the pulley 16 rotatively mounted thereon with roller bearings 17 held in place by lock nuts 18 provided with packing rings 19 to retain grease for lubrication, and locked with cotter pins 20 which pass through holes 21 in the pin 10.

The block is taken down in the following manner: One of the pins 8 is removed, releasing the two sides 6 of the shell at the top. The set screws 23 are backed half a turn only with a wrench, which is provided by the opening 24 in the pin 8, and the pin 8 is further used as a drift, the square head 25 being applied against keys 11 to start them out. Once started, they are easily pulled out as far as the point of the set screws 23 will permit. A light blow with a hammer, first on one end, then on the other, of the pin 10 releases the two parts of the shell 6 owing to the tapered end portion 26. The block is now in three parts, the pin 10 with the sheave on it, and the two parts of the shell, one having the shackle 7 attached. A distinct advantage is thus obtained in having the pin 10 and the sheave mounted together, so that they are not readily taken apart. Otherwise, if they are taken apart, serious objection obtains in that experience proves that the pin and the bearings are dropped in the dirt and become fouled, with the result that they quickly burn out when put into operation. The reassembling of the block is obviously a reversal of the operations just described.

Obviously, changes may be made in the

form, dimensions and arrangement of the parts of my invention, without departing from the principle thereof, the above setting forth only a preferred form of embodiment.

I claim:

1. A demountable pulley block embodying a sheave; a pin for said sheave, said pin being tapered on each end portion, said end portion having a key way slot therethrough; two side mounting members constituting the pulley block shell, each of said members having a tapered hole adapted to receive said sheave pin, and a tapered slot; a tapered key to fit the key way slot in said sheave pin and said slot in said side members; and a releasably mounted shackle operatively disposed to unite the tops of said side members. 70

2. In a pulley block, a sheave mounting pin, said pin having a key slot therethrough, shell side mounting members operatively disposed upon said sheave pin, said mounting members having a tapered key slot therein, and a tapered key disposed in said last-named key slot and through said key slot in said sheave pin, whereby said pulley block 85 may be readily assembled and disassembled. 90

3. In a pulley block, a sheave mounting pin having tapered end portions; two shell side mounting members having tapered bearings which register with said tapered 95 end portions; a tapered pin means which holds said shell mounting members on said pin; and means mounted in said shell members which engage said tapered pin when partially disengaged, whereby said pin 100 is kept in assembled position with said shell members.

In witness whereof, I hereunto subscribe my name this 30 day of April, 1925.
